(57) **CLAIM**

The ornamental design for an expansion valve with solenoid valve, as shown and described.

DESCRIPTION

FIG. 1 is a perspective view of an expansion valve with solenoid valve showing our new design;

FIG. 2 is a rear side perspective view thereof;

FIG. 3 is a front view thereof;

FIG. 4 is a rear view thereof;

FIG. 5 is a right side view thereof;

FIG. 6 is a left side view thereof;

FIG. 7 is a plain view thereof;

FIG. 8 is a bottom view thereof; and,

FIG. 9 is a cross-sectional view taken along line 9-9 in FIG. 3. The broken line showing of portions of the expansion valve forms no part of the claimed design.
